DESIGN FOR A LADY'S GLOVE

Oscar G. Goodhand, New York, N. Y.

Application April 5, 1935, Serial No. 56,227

Term of patent 3½ years

To all whom it may concern:

Be it known that I, Oscar G. Goodhand, a citizen of the United States of America, residing in Manhattan, county of New York, and State of New York, have invented a new, original, and ornamental Design for a Lady's Glove, of which the following is a specification, reference being had to the accompanying drawing, forming part thereof, wherein,

I claim:

The ornamental design for a lady's glove, substantially as shown.

OSCAR G. GOODHAND.
